ADOLPH F. MASCELLINO, OF NORTH BERGEN, NEW JERSEY.

CLOTHES-PIN.

1,275,582.

Specification of Letters Patent. Patented Aug. 13, 1918.

Application filed September 24, 1917. Serial No. 192,983.

To all whom it may concern:

Be it known that I, ADOLPH F. MASCELLINO, a citizen of the Kingdom of Italy, residing at North Bergen, in the county of 5 Hudson and State of New Jersey, have invented certain new and useful Improvements in Clothes-Pins, of which the following is a specification.

This invention relates to clothes pins and 10 more particularly to a clothes pin with means for securing articles independent of the means for fastening the pin on a clothes line.

One of the main objects of the invention 15 is to provide a clothes pin having means for fastening the same on a line and provided with independent means for holding the article of clothing. A still further object is to provide a clothes pin especially adapted for 20 holding unusually heavy articles of clothing, this pin being so constructed as to increase the grip of the holding means on the article in accordance with the increase in the force tending to withdraw the article 25 from the gripping means. A further object is to provide a pin of the character stated which may be produced at relatively small cost and may be used in connection with a clothes line of standard construction. 30 Another object is to provide a pin in which the means for gripping and holding the articles of clothing is also adapted to prevent complete accidental removal of the pin from the clothes line. Further objects will appear 35 from the detailed description.

In the drawings,

Figure 1 is a front view of a clothes pin constructed in accordance with my invention,

40 Fig. 2 is a side view, and

Fig. 3 is a section taken on line 3—3 of Fig. 1.

The body 1 of the pin is carved from wood and is provided with the integral head 45 2. This body is centrally slotted to provide the downwardly extending parallel arms 3 and 4. At the upper end of central slot 5 of the pin are mounted two opposed gripping springs 6 and 7. These springs are 50 formed from properly tempered sheet material, the upper end of the springs being secured in the body of the pin, and the lower ends being turned outwardly so as to permit ready insertion of the springs about a line 55 indicated at 8, the intermediate portion of the springs being slightly bowed or concave

to grip the line securely. These springs constitute a spring clip for securing the pin on a clothes line.

Arm 4 of the pin is provided with a longitudinal slot 9. This slot receives a securing dog 10 which is pivotally secured therein intermediate its ends by a pivot pin 11. The inner end of this dog 10 is of substantially triangular shape to provide a gripping head 60 12. A wire spring 13 is secured in the side bar 14 of arm 4. The inner end of this spring is rounded and is operative in a groove 15 formed in the upper face of dog 10. Spring 13 acts to force the inner portion 65 of the dog 10 downward so as to bring the gripping head 12 into engagement with the gripping face of arm 3, the distance from the pivot pin 11 to the inner end of the dog being somewhat greater than the distance 70 75 apart of the arms 3 and 4.

In using the pin, it is first secured on the line 8 by means of the spring grip formed by the members 6 and 7. After this has been done, the article to be suspended from the line, indicated by 16 in Fig. 1 of the drawings, is inserted between the head 12 of the dog 10 and the inner face of arm 3, after which the article is released. The head 12 serves to grip the article tightly 80 frictionally so as to hold it securely in the body of the pin. The weight of the article 16 serves to exert downward pull on the head 12, thus forcing the head into tight engagement with the portion of the article 85 inserted between the same and arm 3. If a pull is exerted on the article 16, such as would be occasioned by high wind, the grip of head 12 will be increased in proportion to this pull. This eliminates all possibility of 90 the article becoming accidentally detached from the pin, such as frequently happens in using pins of ordinary construction in which the article is confined between the pin and the clothes line so that, when the article is 95 subjected to an unusual force, it pulls easily from between the pin and the line thus causing the article to be detached from the pin. In addition to serving to secure the article in the pin, the dog 10 also serves as a gravity 100 latch or closure member for the lower portion of passage or slot 5 and effectually prevents accidental removal of the pin from line 8 in the event that the springs 6 and 7 105 become disengaged from about the line. By 110 this construction, the article is tightly secured in the pin so as to eliminate all possi-

bility of its becoming accidentally detached therefrom, and the pin itself is secured on the line so as not to be accidentally removed therefrom.

5 What I claim is:

1. In clothes pins, a body having a central slot and spaced arms inclosing said slot, a securing grip secured in the body at the upper end of the slot and adapted to engage about a clothes line so as to secure the pin thereon, and a securing member rockably mounted in one arm of the body and extending across the slot thereof so as to releasably grip an article to be suspended between the inner end of said member and the other arm of the body.
- 10 2. In clothes pins, a body having a cen-

tral slot and lateral arms inclosing the same, a spring grip secured in said body at the upper end of said slot and adapted to engage about a clothes line, a securing dog rockably mounted in one of said arms and extending across the slot adjacent the lower end thereof, and means for normally forcing the inner end of said dog downwardly 20 so as to tightly grip frictionally an article inserted between the same and the other arm of the body.

In testimony whereof I affix my signature in presence of two witnesses.

ADOLPH F. MASCELLINO.
